UNITED STATES PATENT OFFICE

2,474,710

THREAD-TRIMMING AND PULL-OFF MECHANISM FOR SEWING MACHINES

Alfred R. Wood, Bridgeport, Conn., assignor to
The Singer Manufacturing Company, Elizabeth, N. J., a corporation of New Jersey

Application August 21, 1945, Serial No. 611,725

15 Claims. (Cl. 112—252)

1

The present invention relates to improvements in thread-trimming and pull-off mechanism for sewing machines and is especially designed for those machines used for stitching buttonholes, but it is not restricted to this special type, as it is capable of general application in all group-stitch sewing machines.

In sewing machines of this general group, it is common practice to provide a bobbin-thread trimmer and pull-off mechanism for severing the bobbin-thread close to the work at the end of the buttonholing cycle, and pulling from the bobbin a length of thread sufficient to ensure the proper formation of the first stitch of the next buttonhole. For successful operation, it is essential that the thread-trimmer and pull-off mechanism operates unerringly to sever the thread and pull from the bobbin the proper length of thread, so that the shortest possible end of bobbin-thread will be left on the under side of the buttonhole at the beginning and ending of the sewing operation.

It is the primary object of the present invention to provide an improved thread-trimming and pull-off mechanism to secure a uniformly high degree of certainty of operation of the mechanism in sewing operations on all of the various classes of material met with in practice.

It is another object of the invention to provide an improved pull-off which will draw from the bobbin a length of thread insuring the proper concatenation of the sewing threads in the first stitch of the buttonhole and without leaving an excessively long end of bobbin-thread requiring subsequent hand trimming.

Another object of the invention is to provide a mechanism for carrying out the above noted functions, which mechanism is exceedingly compact, cuts the thread close to the work with a high degree of accuracy, and operates over a long period of time without requiring repeated sharpening.

To the attainment of the ends in view, the invention comprises the devices, combinations and arrangements of parts hereinafter described and particularly pointed out in the appended claims.

The features of the invention and the advantages attained thereby will be readily understood by those skilled in the art from the following detailed description of a preferred embodiment of the invention illustrated in the accompanying drawings, in which:

Fig. 1 is a fragmentary right side elevational view of a buttonhole sewing machine embodying the invention.

Fig. 2 is a bottom plan view of the sewing machine.

2

Fig. 3 is a fragmentary bottom plan view of the cross-slide, bobbin-thread trimming and pull-off member and actuating means therefor, showing the bobbin-thread trimming and pull-off member advanced to a position such that the pull-off finger is just engaging the bobbin-thread extending from the thread-case (not shown) up through the usual needle-aperture in the throat-plate, to the last stitch of the finished buttonhole.

10 Fig. 4 is a view similar to Fig. 3, but showing the thread-trimming and pull-off member slightly further advanced so that the pull-off element is at substantially the end of its thread pull-off stroke and the thread-trimming element is about to shear the bobbin-thread.

15 Fig. 5 is a similar view at a still later stage, after the bobbin-thread has been severed, leaving a short thread-end extending from the last stitch in the completed buttonhole down through the needle-aperture in the throat-plate.

20 Fig. 6 is an enlarged top plan view of the assembled thread-trimming and pull-off member.

Fig. 7 is a disassembled perspective view of the thread-trimming and pull-off elements, showing 25 the manner in which the thread-trimming element and the thread pull-off finger are attached to their common carrier.

Fig. 8 represents an enlarged transverse vertical sectional view taken substantially along the 30 line 8—8, Fig. 5.

Fig. 9 represents an enlarged longitudinal vertical sectional view taken substantially along the line 9—9, Fig. 3, showing the lead of the bobbin-thread across the path of movement of the 35 thread pull-off finger from the thread-guide on the thread-case, up through the needle-aperture in the throat-plate to the last stitch of the completed buttonhole.

Fig. 10 represents an enlarged longitudinal 40 vertical sectional view taken substantially along the line 10—10, Fig. 4, showing the lead of the bobbin-thread when the pull-off finger is in position of maximum pull-off.

Fig. 11 represents an enlarged longitudinal 45 vertical sectional view taken substantially along the line 11—11, Fig. 5 showing the thread severed by the cooperation of the thread-trimming knife and the vertically depressed ledger blade.

Referring in detail to the drawings, the invention 50 is disclosed as embodied in a sewing machine of the type adapted to sew "straight" as distinguished from "eyelet-end" buttonholes; the constructive features of the illustrated machine being generally similar to those forming the subject of my United States Patent No. 2,411,493, issued Nov. 19, 1946. The machine-frame is formed with a bed 1 supporting a standard 2 of an over-

hanging bracket-arm terminating in a head 3. Mounted in the head 3 is a vibratory gate 4 carrying an endwise reciprocatory and laterally vibratory needle-bar 5 fitted at its lower end with an eye-pointed thread-carrying needle 6. The needle-bar 5 derives its reciprocations from the usual actuating connections within the head 3, which connections are operated from the main- or arm-shaft (not shown) of the machine. The arm-shaft is connected by a vertical shaft 7 and gearing 8 (Fig. 2) to a loop-taker shaft 9 adapted to carry at its outer end a rotary loop-taker 10 for cooperation with the needle 6 in the formation of lock-stitches. In the machine illustrated in the drawings, the loop-taker 10 is of the rotary hook type and its constructive features are the same as those disclosed in Patent No. 2,426,543, granted August 26, 1947. The lower or bobbin-thread is housed in a thread-case 11 (Fig. 10) which is journaled in the rotary hook 10 and restrained against rotation by an upstanding C-shaped rotation-restraining projection 12 cooperating with stops fixed to the machine-bed. As shown in Fig. 10, the top limb 13 of the rotation-restraining projection 12 is disposed beneath the usual cross-slide 14 and is provided with a leaf-spring member 15 beneath which the bobbin-thread passes in its travel from the bobbin to the work.

The work W to be buttonholed is adapted to be held in a work-clamp comprising the usual lower work-plate 16 and an upper clamp-foot 17. The upper clamp-foot 17 is carried by a resilient member 18 (Fig. 1) which is secured at its inner end on a yoke 19 pivoted at 20 to a lug 21 upstanding from the usual longitudinal slide-plate 22. The upper clamp-foot 17 is yieldingly urged downwardly into contact with the lower work-plate 16 by a coil-spring 23. To provide for separating the upper clamp-foot 17 from the lower work-plate 16 for the insertion and removal of work, the yoke 19 is formed with a rearwardly extending tail-lever 24 adapted to underlie a roller 25 freely journaled on a stud 26 secured to a manually actuated lever 27 fulcrumed at one end on a stud 28 threaded into a supporting bracket 29. At its other end, the lever 27 is fitted with a horizontally disposed stud 30, to the free end of which is attached a suitable treadle-chain connection-element (not shown). Depression of a suitable foot-treadle will cause the lever 27 to swing on the stud 28, against the action of a spring 31, thus causing the roller 25 to engage the tail-lever 24 and swing the yoke 19 about its fulcrum 20, thereby raising the member 18 and the upper clamp-foot 17.

To effect shifting of the work relative to the endwise reciprocatory and laterally vibratory needle 6, the work-clamp is slowly moved in step-by-step fashion, first away from the standard 2 and then towards the standard to cause the first and second rows of side zigzag stitches to be laid side by side in the work. At the opposite ends of its travel, the work-clamp is shifted laterally to space the first and second rows of side stitches. The work-clamp derives its step-by-step movements and its lateral shift from the usual feed-cam 32 carried on a vertically disposed feed-shaft 33 journaled in the bed and the bracket-arm of the machine. The connections between the work-clamp and the feed-cam are identical with those disclosed in my previously mentioned Patent 2,411,493. The feed-cam 32 and feed-shaft 33 are intermittently rotated by means of a one-way-acting clutch, indicated generally as 34, Fig.

2, of the well-known Horton type, which clutch is driven during the operation of the machine by means of an actuating lever 35 (Fig. 3) connected by a link 36 to a rock-lever 37. The rock-lever 37 is carried by the lower end of a vertically disposed rock-shaft 38, to the upper end of which is connected a rock-lever 39 (Fig. 1) connected by a pitman 40 to an eccentric 41 fast on the vertical shaft 7. When the shaft 7 is rotated, the eccentric 41 imparts to the rock-shaft 38 oscillatory movements which, through the rock-lever 37, link 36 and actuating lever 35, operate the clutch 34. The clutch drives the feed-cam 32 and the feed-shaft 33 intermittently in one direction.

The bobbin-thread pull-off and trimmer now to be described comprises a thread pull-off finger 42 and a hardened thread-cutting knife 43, both detachably mounted in substantial coplanar relation on a common oscillatory disk-like carrier 44. The carrier 44 is freely journaled on a pivot-stud 45 depending from the cross-slide 14 at substantially the geometric center of a circular clearance recess 46 cut into the under face of the cross-slide 14. The carrier 44 is yieldingly maintained in contact with the recessed bottom face of the cross-slide 14 and upon the pivot-stud 45 by a leaf-spring support 47 secured by a screw 48 to the cross-slide 14. The thread pull-off finger 42 adjacent its free end is formed with a thread-engaging notch 49 and at its other end is provided with a washer-like shank 50 adapted to enter a segmental positioning-recess 51 formed in the bottom face of the carrier 44. The recess 51 at one side opens into the periphery of the carrier 44, as at 52, Fig. 7, to receive the body-portion of the pull-off finger 42 and provide clearance on opposite sides of the finger, whereby the same may be adjusted relative to the carrier 44 and about the axis of the pivot-stud 45 to effect a change in the timing of the engagement of the pull-off finger with the bobbin-thread. The finger 42 is secured in its selected position of adjustment by the clamp-screw 53 which is threaded into the carrier 44.

Disposed in another recess formed in the top face of the carrier 44, Fig. 6, is the shank 54 of the thread-cutting knife 43, the knife being secured to the carrier preferably by two screws 55. The knife 43 is formed with a sharpened edge 56 which merges into a laterally extending pilot-extension 57. Cooperating with the sharpened edge 56 of the oscillatory knife 43 in severing the bobbin-thread, is a thin, flexible, transversely reciprocatory ledger-blade 58 normally disposed in a transverse clearance-channel 59 (Figs. 4 and 5) cut into the under surface of the cross-slide 14. The ledger-blade 58 is formed with a shank 60 disposed at right angles to the body of the ledger-blade, which shank is secured to a trimmer-actuating slide-bar 61 endwise slidable in a suitable guideway provided in the under surface of the cross-slide 14. The slide-bar 61 carries at one end a rack 62 which meshes with teeth 63 segmentally formed in a portion of the periphery of the carrier 44, whereby the carrier is oscillated about the stud 45 during the actuation of the slide-bar. The means for actuating the slide-bar 61 comprises a bell-crank lever 64 (Figs. 1 and 3) pivoted at 65 to the bed 1 of the machine. The bell-crank lever 64 is operated by a link 66 connected to a vertically disposed lever 67 pivoted at 68 to the machine-bed 1. The lever 67 is adapted to be vibrated when the manually actuated work-

clamp opening lever 21 is depressed by virtue of the stud 30 tracking a cam-slot 69 formed in the lever 61. It will be appreciated that the cam-slot 69 is preferably formed with an actuating portion 70 and a dwell-producing portion 71, so that the link 66 is actuated only during the initial depression of the work-clamp opening treadle and during the time that the stud 30 is tracking the actuating portion 70, to insure that the bobbin-thread is pulled off and cut before the work-clamp is opened to release the work. As fully disclosed in Patent No. 2,426,543, granted August 26, 1947, the work-clamp 17 is provided with a needle-thread cutter and nipper. This cutter and nipper is latched in open or set position by a spring-influenced pivotally mounted latch 72 which is adapted to be tripped by a member 73 fastened on the link 66 when the link 66 is actuated. Thus, when the link 66 is shifted endwise during the initial depression of the work-clamp opening lever 21, both the needle-thread and the bobbin-thread are severed before the work-clamp is opened to release the work.

Referring now to the operation of the bobbin-thread pull-off and trimmer, it will be understood that during the operation of the stitching cycle of the machine, the parts are in the positions shown in Fig. 1. After the stitching is completed, the work-clamp opening treadle is depressed to effect a release of the work. During the initial depression of the treadle and before the work is released, the link 66, through the bell-crank lever 64, imparts an endwise movement to the slide-bar 61 in the direction of the arrow in Fig. 2. The slide-bar 61, through the rack 62 and teeth 63, turns the carrier 44 from the position shown in Fig. 2 to the position shown in Fig. 5. During this travel of the carrier 44, the complete thread pull-off and severing action takes place. The pull-off finger 42 first swings into engagement with the bobbin-thread extending from the last stitch of the buttonhole down to the thread-case, as shown in Figs. 3 and 9. In the continued advance of the carrier 44, the pull-off finger 42 swings to the position illustrated in Figs. 4 and 10, to pull from the bobbin a measured length of thread. During the turning movement of the carrier 44, effected by the endwise movement of the slide-bar 61, the ledger-blade 58 which is fastened on the slide-bar is simultaneously shifted endwise from its retracted position, shown in Fig. 2, into an advanced position, shown in Fig. 4, in which advanced position its sharpened side edge is disposed to cooperate with the sharpened edge 56 of the approaching thread-cutting knife 43 in severing the bobbin-thread. The actual thread-severing takes place during the movement of the parts from the position shown in Fig. 4 to the position shown in Fig. 5, the latter figure illustrating the position of the parts in the extreme advanced position of the carrier 44.

In order to eliminate any possible interference or collision between the approaching leading end of the ledger-blade 58 and the swinging thread pull-off finger 42, the body of the ledger-blade is preferably bent upwardly into a position where it is contained within the transverse guide-channel 59, as shown in Figs. 3 and 10. When disposed within the guide-channel 59, the lower surface of the ledger-blade 58 is located above the level of the upper edge of the pull-off finger 42, and, consequently, as the pull-off finger swings by the end of the ledger-blade, inter-

ference between the two members 42 and 58 is impossible. After the pull-off finger 42 has advanced to a position where interference with the sharpened edge of the endwise moving ledger-blade 58 can no longer occur, the ledger-blade is flexed sidewise downwardly into thread-severing relationship with the thread-cutting knife 43. The required sidewise flexing of the ledger-blade 58 is accomplished by a cam-element which preferably comprises a suitably formed leaf-spring member 74 adjustably secured to the bottom of the cross-slide 14 by a screw 75. It will be appreciated that, as the parts are moved from the position shown in Fig. 3 to the position shown in Fig. 4, the shank 60 of the ledger-blade 58 shifts into contact with the cam-portion of the leaf-spring 74 and the body-portion of the ledger-blade is thereby yieldingly forced downwardly for cooperation with the approaching thread-cutting knife 43. To insure that thread-severing relationship exists between the ledger-blade 58 and the thread-cutting knife, the ledger-blade is purposely flexed below the level of the sharpened edge 56 of the knife 43 into an edgewise-interfering position with said sharpened edge. As the knife swings toward the lowered ledger-blade, the pilot-extension 57 leading the knife 43 engages the beveled free end of the ledger-blade and effects a proper positioning of the knife and ledger-blade for the severing of the thread. As shown in Fig. 8, the pivot 57 functions to deflect the ledger-blade 58 upwardly slightly and at the same time cause the carrier 44 to shift slightly downwardly on its pivot-stud 45, in opposition to the leaf-spring support 41. The resultant action of the two spring-members 47 and 74 is such as to maintain the thread-cutting knife 43 in contact with the ledger-blade 58 during the thread-severing operation.

As explained above, the bobbin-thread pull-off and severing takes place during the initial depression of the work-clamp opening treadle. No special attention of the operator is required in operating the bobbin-thread pull-off and trimming mechanism, inasmuch as the actuating mechanism is designed to insure the proper sequence of operations. Following the removal of the completed work and the insertion of new work, the work-clamp is permitted to close and, through the actuating connections operated by the lever 61, the pull-off finger 42 and the thread-cutting knife 43 are returned to the position shown in Fig. 2. When the pull-off finger 42 swings back to its inoperative position, a measured free beginning-end of bobbin-thread is available to be absorbed in the initial stitches of the next buttonhole. Control of this free beginning-end of the bobbin-thread is effected through the use of the leaf-spring 15 which nips the thread against the edge of the limb 13 of the thread-case rotation-restraining projection 12. As will be seen in Fig. 11, the remaining bobbin-thread-end extending from the last stitch in the buttonhole is sufficiently short to require no further hand-trimming operation.

From the above description, it will be appreciated that I have perfected a bobbin-thread pull-off and trimming mechanism which is exceedingly compact as regards vertical thickness. The features which contribute to this condition are, first, the design of the disk-like carrier 44 with provision for supporting both the pull-off member 42 and the thread-cutting knife 43 within the confines of the bottom and top faces of

the carrier; secondly, the manner in which the second knife member or ledger-blade 58 is arranged to travel in the clearance-channel 59, whereby it is disposed between the throat-plate carrying cross-slide 14 and the carrier 44; and thirdly, the use of the rack and gear drive between the carrier 44 and the transverse slide-bar 61. The principal advantage gained from the compact arrangement of my present invention is that the carrier 44, together with the pull-off member 42 and the knife 43, can be disposed in close proximity to the bottom of the throat-plate and when so disposed, the resultant bobbin-thread-end extending from the work is exceedingly short. The provision of the two opposing spring members 47 and 74 results in yieldingly maintaining the two thread-cutting members 43 and 58 in effective shearing relation during their entire thread-severing action. The resultant scissors action is such as to minimize the resharpening requirements of the two knives 43 and 58.

Having thus set forth the nature of the invention, what I claim herein is:

1. In a sewing machine having a work-support, in combination, stitch-forming mechanism including at least one thread-carrying implement, means for feeding work past said stitch-forming mechanism, complementary thread-severing members disposed at the same side of the work-support and movable relatively to each other into and out of thread-severing relationship, one of said members being confined to movement about a fixed axis and the other of said members being bodily movable in a direction substantially parallel to its thread-severing edge, and means for simultaneously imparting the respective operative movements to said members during the thread-severing action of said members.

2. In a sewing machine having a work-support, in combination, stitch-forming mechanism including a needle and a complementary loop-taker, work-feeding mechanism, complementary thread-severing members disposed at the same side of the work-support and synchronously movable toward each other into thread-severing relationship, one of said members being supported for oscillatory movement and the other of said members being supported for rectilinear movement, and means for imparting the respective operative movements to said members during the thread-severing action of said members.

3. In a sewing machine, in combination, stitch-forming mechanism including a needle and a complementary loop-taker, work-feeding means, a pair of movable thread-cutting members, and means for actuating said thread-cutting members including a movable connection carrying one of said thread-cutting members and operatively connected to the other of said thread-cutting members, whereby the two members are caused to move into cooperation with each other during the severing of the thread.

4. In a sewing machine, in combination, stitch-forming mechanism including a needle and a complementary loop-taker, work-feeding means, a first thread-cutting member, means supporting said first thread-cutting member for oscillatory movement, means for oscillating said first thread-cutting member including a connection operatively associated with said first thread-cutting member, and a second thread-cutting member carried on said connection and disposed to move into cooperative relation with said first

thread-cutting member to sever the thread when said connection is actuated.

5. In a sewing machine, in combination, stitch-forming mechanism including a needle and a complementary loop-taker, work-feeding means, a first thread-cutting member, a carrier supporting said first thread-cutting member and mounted for oscillatory movement, said carrier having a plurality of segmental teeth, means for oscillating said carrier including a connection provided with a rack in mesh with said segmental teeth, and a second thread-cutting member actuated by said connection and disposed to be moved thereby into cooperative relation with said first thread-cutting member to sever the thread when said connection is actuated.

6. In a sewing machine, in combination, stitch-forming mechanism including a needle and a complementary loop-taker having a bobbin-thread, work-feeding mechanism, a pair of bobbin-thread-cutting members, means supporting one of said members for oscillation, means supporting the other of said members for reciprocity, actuating mechanism for imparting operative movements to said two members, whereby they move toward each other into thread-severing relationship, and means rendered effective by the movement of one of said thread-cutting members for urging the effective portions of said two thread-cutting members in shearing relation during the thread-severing action.

7. In a sewing machine, in combination, stitch-forming mechanism including a needle and a complementary loop-taker, work-feeding mechanism, a first thread-cutting member, means supporting said first thread-cutting member for oscillatory movement, means for oscillating said first thread-cutting member including a connection operatively associated with said first thread-cutting member, a flexible second thread-cutting member carried by said connection and disposed to move into cooperation with said first thread-cutting member to sever the thread when said connection is actuated, and a cam-element disposed in the path of travel of said second thread-cutting member for flexing said second thread-cutting member into shearing relation with said first thread-cutting member during the thread-severing action.

8. In a sewing machine, in combination, stitch-forming mechanism including a needle and a complementary loop-taker having a bobbin, work-feeding mechanism, an oscillatory bobbin-thread pull-off and cutting device having a pull-off member and a first knife member, a second movable knife member adapted to cooperate with said first knife member in severing the bobbin-thread, and means operatively associated with said bobbin-thread pull-off and cutting device and said second knife member for initially imparting oscillatory movement to said bobbin-thread pull-off and cutting device to cause the pull-off member to engage and pull-off a measured length of bobbin-thread and to impart a further oscillatory movement to said bobbin-thread pull-off and cutting device and simultaneously to move said second knife member toward said first knife member to effect a severing of the bobbin-thread.

9. In a sewing machine, in combination, stitch-forming mechanism including a needle and a complementary loop-taker having a bobbin, work-feeding mechanism, a bobbin-thread pull-off member and a first knife member both disposed substantially in the same plane, a movable common carrier for said members, a second movable

knife member adapted to be shifted into cooperative relation with said first knife member in severing the bobbin-thread, said second knife member being normally disposed at a level out of range of said bobbin-thread pull-off member, means for imparting operative movements to said carrier and said second knife member, and means to deflect said second knife member into thread-shearing relation with said first knife member when said pull-off member has moved beyond said second knife member.

10. In a sewing machine, in combination, stitch-forming mechanism including a needle and a complemental loop-taker having a bobbin, a throat-plate, work-feeding mechanism, a bobbin-thread pull-off member and a first knife member both disposed substantially in the same plane, a common carrier for said two members mounted beneath said throat-plate for oscillatory movement, a second knife member supported to move toward said first knife member for cooperation therewith in severing the thread, said second knife member being normally disposed at a level above the path of movement of said bobbin-thread pull-off member, means for imparting operative movements to said carrier and said second knife member, and means to deflect said second knife member downwardly into thread-shearing relation with said first knife member after said pull-off member has moved beyond said second knife member.

11. In a sewing machine, in combination, stitch-forming mechanism including a needle and a complemental loop-taker provided with a bobbin, a throat-plate having a clearance-channel, a carrier supported beneath said throat-plate for oscillatory movement, a bobbin-thread pull-off member and a first knife member both secured to said carrier, means for actuating said carrier including a reciprocatory slide-bar operatively connected to said carrier, a second knife member mounted on said slide-bar and disposed to move toward said carrier into cooperative thread-severing relation with said first knife member, said second knife member having its effective portion disposed to travel in the clearance-channel of said throat-plate to avoid interference with said oscillatory pull-off member, and means for moving said second knife member into shearing relation with said first knife member after said pull-off member has moved beyond said second knife member.

12. In a sewing machine, in combination, stitch-forming mechanism including a needle and a complemental loop-taker provided with a bobbin, a throat-plate, a carrier supported beneath said throat-plate for oscillatory movement, substantially coplanar bobbin-thread pull-off and first knife members secured to and extending substantially radially from said carrier, means for oscillating said carrier including an endwise reciprocatory slide-bar operatively connected to said carrier, a second knife member mounted on said slide-bar and arranged to move toward said carrier into cooperative thread-severing relation with said first knife member, said second knife member having its effective portion disposed at a level between said carrier and said throat-plate to avoid collision with said thread pull-off member during its active stroke, and a cam-element disposed in the path of travel of said second knife member to deflect the same into shearing relation with said first knife member during the thread-severing action of said knife members.

13. In a sewing machine, in combination, stitch-forming mechanism including a needle and a complemental loop-taker provided with a bobbin, a throat-plate having a clearance recess formed in the bottom surface thereof, a disk-like carrier oscillatably supported within said clearance recess with the bottom face of said carrier substantially flush with the bottom surface of said throat-plate, substantially coplanar bobbin-thread pull-off and first knife members secured to said carrier and operable within said clearance recess, means for oscillating said carrier including an endwise reciprocatory slide-bar operatively connected to said carrier, a second knife member carried by said slide-bar and arranged to move toward said carrier into cooperative thread-severing relation with said first knife member, said second knife member having its effective blade-portion disposed at a level between said carrier and said throat-plate to avoid collision with said thread pull-off member during its active stroke, and a cam-element secured to said throat-plate and disposed in the path of travel of said second knife member to deflect the same downwardly into shearing relation with said first knife member during the thread-severing action of said knife members.

14. In a sewing machine, in combination, with stitch-forming mechanism including a needle and a complemental loop-taker provided with a bobbin, and a throat-plate, of a bobbin-thread pull-off and trimming device, including an oscillatory disk-like carrier, a blade-like thread trimming knife flatwise secured to said carrier, a blade-like thread pull-off member also flatwise secured to said carrier in a position in advance of said knife in the direction of the active stroke of said carrier, said pull-off member and said trimming knife having their effective edges disposed in substantially the same plane, and actuating means operatively connected to said carrier.

15. In a sewing machine, in combination, with stitch-forming mechanism including a needle and a complemental loop-taker provided with a bobbin, and a throat-plate, of a bobbin-thread pull-off and trimming device, including an oscillatory disk-like carrier having a plurality of gear teeth formed in its periphery, a blade-like thread trimming knife flatwise secured to said carrier, a blade-like thread pull-off member also flatwise secured to said carrier in a position leading said knife in the direction of the active stroke of said carrier, said pull-off member and said knife having their effective edges disposed in substantially the same plane, means for effecting a relative adjustment between said thread trimming knife and said pull-off member, and means for actuating said carrier including a rack in mesh with the gear teeth of said carrier.

ALFRED R. WOOD.
